UNITED STATES PATENT OFFICE.

AAGE NYROP, OF COPENHAGEN, DENMARK.

TRUSS.

Application filed June 21, 1926, Serial No. 117,555, and in Germany July 10, 1925.

My invention relates to a truss with a spherical pad disposed at the elastic end of the truss. The essential feature of the invention lies in that a loose stem is provided, 5 passing through a hole in the elastic end, to which stem the ball of the pad, preferably made of solid caoutchouc, is rigidly secured by its neck. The stem is, at the one end by the semispherically curved surface 10 of a button on the one side of the elastic end, and at the other end by the likewise semispherically curved surface of the neck of the pad on the opposite side of the elastic end, held swivelling in a kind of ball bearing and attached with its button shaped head in such a manner to the strap of the truss, that by lever action it will force the pad 15 into the port of the hernia.

In the accompanying drawing the subject 20 of the present invention has been exemplified,

Fig. 1 being a perspective view of the truss,

Fig. 2 being a plan view thereof.

The pad consists of a ball 1 which may 25 be made of, for example, caoutchouc and is fitted to a stem 3 having a button 4. In case of very fat persons the stem pad may have a neck 2.

The button 4 is convex on its inner side. 30 The pad is fitted in the one end of the truss spring 5 which, for this purpose, is provided with a buttonhole shaped slot (see Fig. 1.)

In order to secure the pad in its place 35 swivelling a breech plate 8 having a bend-over 9 and a pin 7 is provided in known manner so that when the pad is in its posi-

tion in the truss spring 5, it can freely move to all sides, as the longitudinal axis of the pad can travel through a cone with the head 40 4 as fulcrum.

The free end of the strap 11 may be buckled in known manner to the spring 5 or, what often will be more advantageous, 45 to the button 4 of the pad itself.

It will be evident from the foregoing description and the drawing that the pad will permanently exert the necessary pressure, even if the truss should shift on the patient's body, as the spherical surface 1 50 will exert the pressure in a diametral direction, even if the pad itself should have a more or less slanting position. If the rupture, for example, should have a downward port, the pad will, owing to its spherical 55 shape, tend to exert an upward pressure.

Having now described my invention, what I claim as new and desire to secure by Letters Patent is:—

Improvement in trusses with spherical 60 pad at the end of the spring, consisting in a loose stem passing through a hole in the end of the spring, the spherical pad by means of its neck rigidly attached to said stem, a button on the one side of said hole having a spherical surface bearing against the one 65 end of said stem, the neck of the pad having a spherical surface likewise bearing against said stem, the closing strap adapted to be attached to said button.

In testimony whereof I affix my signature.

AAGE NYROP.
